UNITED STATES PATENT OFFICE.

DAVID PETRI-PALMEDO, OF BRIDGEPORT, CONNECTICUT, ASSIGNOR TO ELECTRIC COMPOSITOR COMPANY, OF NEW YORK, N. Y., A CORPORATION OF NEW JERSEY.

MATRIX-DISTRIBUTING MECHANISM.

1,221,088.

Specification of Letters Patent.

Patented Apr. 3, 1917.

Application filed August 9, 1915. Serial No. 44,520.

To all whom it may concern:

Be it known that I, DAVID PETRI-PALMEDO, a citizen of the United States, residing at Bridgeport, in the county of Fairfield and 5 State of Connecticut, have invented a certain new and useful Improvement in Matrix-Distributing Mechanism, of which the following is a full, clear, and exact description.

Certain forms of matrix distributing 10 mechanism, for example, that which is shown and described in the Bellows Patent No. 921,065, are organized to push a line of matrices along distributing rails until the head matrix in the line is temporarily stopped in 15 a true vertical position with its lower end over a gap or hole, and its upper end directly below a vertically movable transfer blade. This transfer blade, as it comes down engages the top of the said head matrix and 20 pushes it down, thereby transferring it from the distributing rails into the embrace of another support, as for example, a cage, as shown in said prior patent.

This invention is for the purpose of preventing the matrix-transferring movement of said blade, unless the said head matrix is in the proper position to be transferred; and this is desirable because, if the transfer blade moves down upon a matrix which by 25 chance is not properly positioned below it, said matrix will be bent, and a bent matrix creates a lot of trouble in any line casting machine of which said distributing mechanism is a part. The invention as shown is 30 particularly contrived for use as an addition to the distributing mechanism of the above mentioned prior patent, but obviously its use is not restricted to this particular mechanism.

35 The invention includes a dog which automatically seeks a position such as prevents the spring-induced downward movement of the transfer blade, and means whereby the head matrix in reaching the proper position 5 will cause the withdrawal of said dog; and the invention consists in the combination of parts shown in the drawings and hereinafter described and definitely pointed out in the appended claims.

40 In the drawings, Figure 1 is a front elevation of so much of the distributing mechanism of a linotype machine of the character stated as is necessary for the understanding of the present invention, which is also shown; Fig. 2 is a sectional side view in the

plane of line 2—2 on Fig. 3; Fig. 3 is a top plan view of the mechanism which forms the principal part of the present invention; Fig. 4 is an enlarged front view, partly sectioned, of the present invention; Fig. 5 is an 60 enlarged front view of a part of said invention; Fig. 6 is a side view partly sectional of some of the parts of said invention; and Fig. 7 is a sectional plan view in the plane of line 7—7 on Fig. 4.

65

Referring to the parts by reference characters, 10 represents the distributor rails by which a line of matrices M may be supported, and along which they may be moved by a follower 12 so as to carry the head (right hand) matrix against the vertical left face of a stop member 14, and over a recess or gap 10^a between the ends of the distributing rails, and said stop member.

70

20 represents a vertically movable transfer blade whose function is to engage the top of the head matrix and push it down through said recess 10^a, and into the embrace of a cage 17. This transfer blade is connected with a vertically movable guided slide 21 80 which slide is engaged by one end of a lever 22. This lever is under the influence of a spring 23 tending to rock it so as to move said slide and consequently said transfer blade down; and a cam 24 engages said 85 lever for the purpose of moving it and the slide and blade in the opposite direction.

All of the parts above described are parts which either in the precise form shown or some equivalent form are to be found in 90 said prior patent.

The matrices M are of familiar form and each has a pair of ears m which respectively project forward and backward near its upper end, and another pair of ears m' which 95 respectively project forward and backward, near its lower end. While the matrices necessarily vary in thickness, the ears are preferably of the same thickness on all matrices,—and preferably they are so arranged that the right hand faces of said ears are in the same vertical plane as the right hand face of the matrix. These lower ears are the parts of the matrices which rest and slide on the distributing rails 10.

100

In the vertical left face of this stop member 14 is a vertical groove 14^c. In this groove lies a pivoted dog 15 which is pivoted close to the lower end of said stop member, and which extends upward in and beyond 110

2
said groove to a position such that its upper end may engage beneath a shoulder 21^a which is rigidly fixed to said transfer blade; and a spring 15^c acts to move the dog to this position (shown in Fig. 4) when possible. For convenience this stop shoulder 21^a is a part of the slide 21 with which the transfer blade is connected.

Near its lower end, this pivoted dog 15 has a vertical slot 15^a in which lies the middle part of a lever 16,—said lever being pivoted midway between its ends to said dog, by means of the pivot pin 16^b. The upper and lower ends of this lever are formed with short lugs 16^a, 16^d, which normally project to the left beyond the plane of the stop surface 14^a. When the head matrix is in the proper vertical position in contact with said stop surfaces, it will have engaged both the upper and lower lugs of said lever 16, and pushed both ends evenly to the right. In fact, said matrix comes in contact with both of said lugs before it reaches said stop surface, and by the time the matrix has come into contact with said stop surface it will have pushed equally against both lugs of this lever. Because of this even pressure the lever will not rock on its pivot, but, instead, the dog will be rocked on its pivot and will thereby be withdrawn with the transfer blade.

But if the head matrix in the line is not in a vertical position as it comes up to said stop member, this action will not take place. For example, if the top of the matrix is in advance of its bottom, said matrix will strike the upper lug of the lever 16, and by the time the upper end of the matrix comes against the stop surface it will have rocked said lever 16 upon its pivot; but this rocking movement does not cause any such movement of the dog 15 as will withdraw it from beneath the transfer blade. Therefore, the transfer blade can not come down.

So, again, if it is the lower end of the matrix in advance of the upper end, said lower end will by the time it has come against the stop member, have merely rocked the lower end of lever 16 to the right, and this will not have caused the releasing movement of the dog. In fact, the matrix must strike and apply equal pressure to both the upper and lower lugs of the lever 16 in order that thereby there may be produced such a rocking movement of the dog 15 as will release the transfer slide to the action of its operating spring.

There are two matrix sustaining levers 25 lying in vertical recesses in the left face of the stop member 14, and pivoted near their upper ends thereto. Each has at its lower end a toe 25^a which normally extends part way across the gap 10^a and under the lower ears of the head matrix, when the latter is

near the stop member 14. The same pin 16^b which pivotally connects lever 16 with the dog 15 extends forwardly and backwardly through large holes 14^e in the stop member 14 and into vertical slots 25^b in these two levers. When, therefore, the matrix by pressing against the two lugs of the lever 16 rocks the dog 15 to an inoperative position, these levers will likewise be rocked so that their toes will be withdrawn from beneath the ears of the head matrix. Nothing now interferes with the downward movement of the transfer blade, or with the resulting downward movement of the head matrix through the gap 10^a; and said matrix is likewise in a position to be engaged and so moved by said transfer blade.

The above described mechanism prevents any matrix-transferring movement of the transfer blade unless the head matrix is in the right position to be transferred, and likewise it prevents the head matrix from falling through the recess 10^a at any time except when the transfer blade has been released from restraint.

Having described my invention, I claim:

1. In matrix distributing mechanism, the combination of matrix supporting rails, a vertical stop member adjacent to but at a short distance beyond the ends of said rails, means for moving a line of matrices along said rails to carry the head matrix of said line against said stop member, and a spring-actuated vertically movable transfer blade, with a dog normally preventing the spring-induced descent of said transfer blade, and means for withdrawing said dog,—which means comprise a member which projects into the path of said matrix and is adapted to be moved thereby as said matrix moves toward and against said stop member.

2. In matrix distributing mechanism, the combination of matrix supporting rails, a vertical stop member adjacent to but at a short distance beyond the ends of said rails, means for moving a line of matrices along said rails to carry the head matrix of said line against said stop member, and a spring-actuated vertically movable transfer blade, with a dog normally preventing the spring-induced descent of said transfer blade, and means for withdrawing said dog,—which means comprise a rocking member having two lugs which project into the path of said head matrix near the upper and lower ends thereof and are both adapted to be engaged and moved equally by the head matrix when it is in a vertical position and just as it comes into engagement with said stop member.

3. In matrix distributing mechanism, the combination of matrix supporting rails, a vertical stop member adjacent to but at a short distance beyond the ends of said rails, means for moving a line of matrices along said rails to carry the head matrix of said

line against said stop member, and a spring actuated vertically movable transfer blade, with a pivoted dog adapted to engage a shoulder fixed to said transfer blade, and thereby prevent the spring induced descent of said transfer blade, a lever which is centrally pivoted to said dog and has near its upper and lower ends lugs which are projected into the path of the upper and lower ends of the head matrix whereby said head matrix, if occupying a vertical position, will engage both ends of said lever and move both ends equally and therefore move with the dog to release said transfer blade.

15 4. In matrix distributing mechanism, the combination of matrix supporting rails, a vertical stop member adjacent to but at a short distance beyond the ends of said rails, means for moving a line of matrices along said rails to carry the head matrix of said line against said stop member and a spring

actuated vertically movable transfer blade, with a dog normally preventing the spring induced descent of said transfer blade, and means for withdrawing said dog,—which 25 means comprise a part which projects into the path of said matrix and is adapted to be moved thereby as said matrix moves toward and against said stop member, a pivoted matrix supporting lever having at its lower 30 end a toe adapted to normally project part way across the gap between the ends of said distributing rails and stop member, and means connecting said lever with said dog whereby they must move in unison.

35 In testimony whereof, I hereunto affix my signature in the presence of two witnesses.

DAVID PETRI-PALMEDO.
